UNITED STATES PATENT OFFICE.

HJALMAR S. ANDERSON, OF PITTSBURG, PENNSYLVANIA.

INTERNAL-COMBUSTION ENGINE.

No. 873,650.

Specification of Letters Patent.

Patented Dec. 10, 1907.

Application filed December 28, 1906. Serial No. 349,824.

To all whom it may concern:

Be it known that I, HJALMAR S. ANDERSON, a citizen of the United States, and a resident of Pittsburg, in the county of Allegheny and State of Pennsylvania, have invented a new and Improved Internal-Combustion Engine, of which the following is a full, clear, and exact description.

This invention relates to certain improvements in internal combustion engines, and more particularly to means whereby the engine cylinder may be cooled by air delivered to the carbureter and also by means of the explosive mixture delivered to the inlet valve.

The object of the invention is to provide an improved construction wherein the air delivered to the carbureter is heated by radiation and a richer mixture thus produced in the carbureter, and this richer mixture is also heated by radiation from the engine cylinder before being ignited within said cylinder.

The invention consists in certain features of construction and combination of parts, all of which will be fully set forth hereinafter and particularly pointed out in the claims.

Reference is to be had to the accompanying drawings forming a part of this specification, in which similar characters of reference indicate corresponding parts in all the figures, in which

Figure 1 is a side elevation of the engine cylinder, the outer jacket being shown in section; Fig. 2 is a longitudinal section through the engine cylinder and jacket; Fig. 3 is a transverse section on the line 3—3 of Fig. 1; Fig. 4 is a transverse section on the line 4—4 of Fig. 2; and Fig. 5 is a development of the outer surface of the cylinder.

In my improved construction I employ a cylinder 10 having a cylinder head 11 either rigidly secured thereto or integral therewith, and within the head is located the inlet valve 12 and the exhaust valve 13. These valves are supported by valve stems 14 and 15, and may be operated by means of cams or in any other suitable manner well known in the art. Adjacent the inlet valve is located the spark plug 16 for igniting the explosive mixture, and within the cylinder operates any suitable form of piston 17 and piston rod 18. As these parts do not constitute an essential portion of my invention, and as any suitable construction may be employed, further description of the specific details illustrated is not thought to be necessary.

The outer surface of the cylinder is provided with a plurality of flanges so arranged as to form a plurality of passages intermediate the cylinder and the jacket 19, which latter is provided with a plurality of flanges or other heat-diffusing elements 20 of any suitable character for radiating the heat, and thus maintaining the cylinder at the desired temperature. The flanges upon the outer surface of the cylinder 10 not only serve to form the passages above referred to, but also serve to support and hold in place the jacket 19. Rigidly secured to the jacket, adjacent the end of the cylinder farthest from the inlet and exhaust valves, is secured a conduit 21 communicating with the space between the cylinder 10 and the jacket 19 and having its outer surface provided with a plurality of radial flanges or other heat-diffusing elements 22, for radiating the heat of the fluid passing through said conduit. The conduit is sub-divided by a partition 23 to form two separate passages, and its outer end is provided with a flange 24 whereby the end of the conduit may be connected directly to the carbureter or to a separate conduit 25 leading to said carbureter. The two passages within the conduit 21 communicate with the two separate passages between the cylinder and the jacket, and the carbureter is so constructed and connected to the conduit that air may be delivered to it through one of the passages of the conduit, and the charged air forming the explosive mixture returned from said carbureter through the other passage.

The arrangement of flanges upon the outer surface of the cylinder 10 is clearly illustrated in the development of the outer surface of said cylinder shown in Fig. 5. The opposite ends of the cylinder are provided with flanges 26 of greater thickness and strength than the remaining flanges, and these serve for engagement with the jacket at the ends of the latter to support said jacket and hold it in the desired position. One of the flanges 26, namely, the one farthest from the inlet and exhaust valves of the engine, is imperforate while the other flange 26 is provided with an opening 27 communicating directly with the atmosphere and serving as an inlet for the air which is to be delivered to the carbureter. Extending from one flange 26 to the opposite one, and located adjacent the supply passage 27, is an imperforate flange 28, which, coacting with a

second flange 29 lying substantially parallel thereto throughout the greater portion of its length, forms a passage 30 extending longitudinally of the cylinder. Lying substantially parallel to the end flanges 26 is a plurality of circumferential flanges 31^a, 31^b, 31^c and 31^d, each of which is connected to the longitudinal flange 29 and all of which except the flange 31^d terminate a short distance from the longitudinal flange 28. Intermediate the flanges 31^a and 31^b and intermediate the flanges 31^b and 31^c, are two flanges 32^a and 32^b lying parallel thereto and connected to the longitudinal flange 28 and spaced a short distance from the longitudinal flange 29. The flange 29 terminates at the flange 31^a, which lies farthest from the inlet and exhaust valves of the engine, and the passage 30 between the flanges 28 and 29 thus communicates with a passage 33 lying between the end flange 26 and the adjacent flange 31^a. Within the passage 33 is a short longitudinal flange 34 extending from across said passage and adapted to engage with the inner end of the partition 23 of the conduit 21, whereby the two passages of said conduit communicate with the passage 33 upon different sides of said flange or partition 34. As the flange 31^a terminates a short distance from the flange 28, a passage is formed, whereby communication is established between the space below the flange 31^a and the passage 33^a lying between the flange 31^a and the flange 32^a. The passage 33^a extends from the partition or flange 28 around the cylinder to the partition or flange 29 and communicates with the passage lying between the flanges 32^a and 31^b, which in turn communicates with the passages lying above each of the next successive pairs of adjacent flanges above referred to. Adjacent the flange 31^c is a flange 32^c which terminates a short distance from the flange 28, but also terminates a short distance from the flange 29; this construction being necessary to permit the passage of the gas around the bushing 35 through which is inserted the spark plug 16.

Above the flange 32^c is a flange 31^d in engagement with both of the flanges 28 and 29, and having an opening leading from the passage between the flanges 32^c and 31^a to the chamber 36 at the end of the cylinder and adjacent the inlet and outlet valve casings. This chamber is sub-divided by a circumferential partition 32^d lying intermediate the partition 31^d and the terminal flange 26, and having a plurality of passages therethrough. The space intermediate the partition 32^d and the terminal flange 26 is sub-divided by a longitudinal partition 37 and again by the bushing 38 surrounding the exhaust port 39. The casing of the inlet valve is provided with an inlet port 40 leading from the valve chamber to the passage intermediate the parti-

tions 31^d and 32^d, and this last mentioned passage communicates with the passage intermediate the partition 32^d and the terminal flange 26.

By means of the partitions, passages and ports above referred to, the air may freely flow through the passages 30 and 33 to one of the passages in the conduit 21, as indicated by the arrows on Fig. 5. The air becomes charged with the fuel at the carbureter and flows back to the engine through the remaining passage of the conduit 21 and is delivered into the passage 33 upon the opposite side thereof to the inlet passage of the air. The fluid mixture flows almost entirely around the cylinder after flowing into the passage 33 and travels almost entirely around the cylinder a second time. It then flows to the passage intermediate the flanges 32^a and 31^b, and so on back and forth around the cylinder until it reaches the inlet valve 40 and is admitted to the cylinder through the inlet valve 12, following the path also indicated on Fig. 5 by means of the arrows. It will thus be noted that the atmospheric air passes lengthwise of the cylinder and once around the same before being delivered to the carbureter. This serves to abstract certain heat from the cylinder wall, and this heat is in turn partially radiated to the outside atmosphere by means of the flanges 20. More of the heat within this air is radiated while said air is flowing through the conduit 21, but when the air arrives at the carbureter it is still in a somewhat heated condition. By delivering the air to the carbureter in a somewhat heated condition, the gasoline or other fuel is much more readily evaporated and a far richer mixture is obtained. The vaporizing of the fuel serves to further reduce the temperature of the air, and the air thus cooled by radiation and vaporization is then circulated back and forth around the cylinder of the engine to thoroughly cool the latter and to heat the fuel to such a temperature that the most advantageous results may be secured. The incoming air and also the explosive mixture is circulated not only around the outer surface of the cylinder, but also in contact with the ends thereof, and the cylinder is cooled and maintained in the proper working condition.

It is evident that any number of partitions or flanges may be provided and the passages arranged in any suitable manner within the scope of the appended claims, as I do not wish to be limited to the specific construction illustrated and described.

Having thus described my invention, I claim as new and desire to secure by Letters Patent:

1. An internal combustion engine, including a cylinder, a carbureter, and two conduits, both of said conduits encircling said cylinder and exposed to the heating action thereof,

and one of said conduits having the inlet end thereof in communication with a suitable source of air supply and the outlet end connected to the carbureter, and the other of 5 said conduits having the inlet end thereof connected to said carbureter and the outlet end thereof connected to the interior of the cylinder.

2. An internal combustion engine, including 10 a cylinder, a jacket surrounding the same and forming therewith two conduits, and a carbureter, one of said conduits serving to deliver uncarbureted air to said carbureter and the other conduit serving to deliver carbureted air from the carbureter to the interior of 15 the cylinder.

3. An internal combustion engine, comprising 20 a cylinder having a plurality of radial flanges, a jacket surrounding said cylinder and in engagement with said flanges, said flanges being so disposed as to form with the cylinder and jacket two independent passages, means for establishing communication 25 between both of said passages and a carbureter, means for establishing communication between one of said passages and the interior of the engine cylinder, and means for establishing communication between the other of 30 said passages and the outside atmosphere.

4. An internal combustion engine, comprising 35 a cylinder, a jacket surrounding the same and spaced therefrom, a plurality of partitions intermediate said cylinder and said jacket and forming a plurality of independent passages, and a conduit connected

to said jacket and having separate passages connecting to the corresponding passages between the cylinder and jacket, one of the passages of the jacket and one of the passages of 40 the conduit serving for the delivery of uncarbureted air to the carbureter, and one of the passages of each serving for the delivering of the carbureted air to the cylinder.

5. An internal combustion engine, comprising 45 a cylinder, means coöperating therewith to form two independent passages, and means for connecting one end of both of said passages to a carbureter, the opposite end of one of said passages communicating with the interior of the engine and the opposite end of 50 the other passage communicating with a source of air supply.

6. An internal combustion engine, comprising 55 a cylinder, a jacket spaced therefrom, partitions or flanges coöperating with said cylinder and jacket to form a plurality of independent passages, and means for connecting one end of one passage to one end of the opposite passage, said means including a carbureter, the other end of one of said passages 60 communicating with a source of air supply, and the other end of the other passage communicating with the interior of the cylinder.

In testimony whereof I have signed my name to this specification in the presence of 65 two subscribing witnesses.

HJALMAR S. ANDERSON.
